CLAIM

The ornamental design for a battery cover for a lift truck, as shown and described.

DESCRIPTION

FIG. 1 is a perspective view of the battery cover for a lift truck as viewed from the right rear and above with the rear of the cover defined by an operator's position on the lift truck;

FIG. 2 is a rear elevational view thereof;

FIG. 3 is a front elevational view thereof;

FIG. 4 is a left side elevational view thereof;

FIG. 5 is a right side elevational view thereof;

FIG. 6 is a top plan view thereof; and,

FIG. 7 is a bottom plan view thereof.
